UNITED STATES PATENT OFFICE.

THOMAS DANQUARD, OF NEW YORK, N. Y., ASSIGNOR TO AUTO PNEUMATIC ACTION COMPANY, A CORPORATION OF NEW YORK.

MUSICAL INSTRUMENT FOR USING TWO NOTE-SHEETS.

1,159,750.

Specification of Letters Patent.

Patented Nov. 9, 1915.

Application filed February 6, 1913. Serial No. 746,516.

To all whom it may concern:

Be it known that I, THOMAS DANQUARD, a citizen of the United States, residing at New York, in the county of New York and State of New York, have invented a new and useful Musical Instrument for Using Two Note-Sheets, of which the following is a specification.

The object of this invention is to provide an operating mechanism for musical instruments whereby playing can be carried on substantially continuously, or the playing can be switched from one piece of music to another without appreciable loss of time.

15 The device is especially adapted for use in connection with moving picture shows where the time employed in rewinding a note-sheet after playing and the placing of a new note-sheet in position, often occasions an awkward pause at an inopportune time.

20 The invention consists substantially of a playing mechanism having two trackers, means for drawing a separate perforated note-sheet forward over each tracker for playing and backward for rewinding, and means whereby one note-sheet can be drawn forward on one tracker and the other note-sheet drawn backward on the other tracker, simultaneously if desired; and also of 25 means whereby the playing can be switched from one note-sheet to the other. By this arrangement, the playing can be carried on practically continuously, as when one note-sheet is being drawn forward for playing, the other note-sheet can be rewound and a new music roll interposed and the playing can be switched to the new note-sheet when 30 the first note-sheet has been drawn forward its entire length. Also, playing can be switched from one note-sheet to the other at any time so as to change the tune or melody which sometimes is desirable so that the operator can change the tune to follow changes in scene.

40 45 The invention may also be put to other uses besides those described.

The invention is shown in the accompanying three sheets of drawings in which,

50 Figure 1 is a partial front elevation of the mechanism; Fig. 2 is an enlarged elevation partly in section illustrating the valve construction; Fig. 3 is a side elevation thereof; Fig. 4 is a sectional elevation through the spool box; Figs. 5 and 6 are sectional views through the switch mechanism; and

Figs. 7 and 8 are rear views of the switch and switch block.

Referring to the drawings and in detail, A designates a spool box in which are arranged two trackers B and C, each having a set of note controlling or playing apertures. As shown, the trackers are arranged one above the other, but this arrangement is not necessary, as they may be arranged in any convenient relation to each other. A set of the usual music roll bearings 10—10 is arranged in the spool box in which a music spool D having a perforated note-sheet E wound thereon can be placed. F designates a take-up roll for drawing said note-sheet forward over the tracker B, which take-up roll is journaled in bearings in the spool box. The take-up roll F is provided with a gear 11 engaging which is a pinion 12 mounted on the end of an axially movable shaft 13 which has a sprocket wheel 14 on the end thereof to which power is supplied by sprocket chain 15 and sprocket wheel 16 arranged on the shaft 17 of a pneumatic motor G secured to the frame of the machine. This motor may be of the usual type and preferably is arranged with its pneumatics extending horizontally. Secured on said shaft 13 is a grooved collar 18 having a projecting pin 19. Loosely mounted on said shaft 13 is a sprocket gear 20 which is engaged by a sprocket chain 21 which runs around a pinion 22 which is secured to the right-hand bearing or shaft which supports the music spool D. The sprocket gear 20 is held in place axially by an arm which engages a groove therein.

A lever 23 is pivoted to a bearing 24 and has a pin 25 engaging the groove in the collar 18. The sprocket gear 20 has a pin 26 with which the pin 19 can engage when the grooved collar is at its right-hand position. By this arrangement, when the upper end of the lever is thrown to the left, the pinion 12 will engage the gear 11 and as the motor G is operated, the take-up roll F will be rotated to draw the note-sheet forward over the tracker B and wind the same up on said roll, and as the pin 19 on the grooved collar 18 does not engage the pin 26 on the sprocket 20 during this operation, the sprocket 20 will not be rotated. When the upper end of the lever is thrown to the right, the pinion 12 will be disengaged from the gear 11 and the grooved collar will be

moved to the right so that its pin 19 will engage the pin 26 on the sprocket 20; hence power will be transmitted from the motor G to turn the music spool D in a direction to draw the perforated note-sheet back over the tracker and rewind the same.

These parts, with the exception of the construction of the lever 23, as shown, are constructed in accordance with the design employed in a player piano well-known to the trade and need not be herein further described.

Also arranged in connection with the lower tracker C is a similar gearing or mechanism comprising bearings 100—100 in which a music spool D' can be arranged so that a perforated note-sheet E' can be drawn over the lower tracker C and wound up on a take-up roll F'. This take-up roll F' has a gear 110 thereon engaged by a pinion 120 mounted on a slideable shaft 130 having a sprocket wheel 140 thereon which is driven by a sprocket chain 150 from a sprocket gear 160 mounted on the shaft 170 of a pneumatic motor G'. This pneumatic motor G' preferably is arranged to stand vertically. Secured on said slideable shaft 130 is a grooved collar 180. A sprocket wheel 200 is loosely placed on said shaft 130 and connects by a sprocket chain 210 to a sprocket pinion 220 mounted on the right-hand bearing 100. The lower end of the lever 23 is provided with a pin 250 which engages into the groove of the collar 180 and the sprocket 200 is provided with a pin 260 which can be engaged by the pin 190 of the grooved collar 180. Thus it will be seen that, when the upper end of the lever 23 is rocked to the left, the upper mechanism will be operative to draw the note-sheet E forward over the tracker B and the lower mechanism will be operative to draw the note-sheet E' backwardly on the lower tracker C and rewind the same on the take-up roll F'. On the other hand, if the upper end of the lever 23 is shifted to the right, the upper mechanism will be operative to draw the note-sheet E backwardly over the upper tracker B and rewind the same on the music spool D, while the lower mechanism will be operative to draw the perforated note-sheet E' forward over the lower tracker C on to the take-up roll F'.

To operate the lever 23 the following mechanism is provided: A short shaft 27 is journaled in the left of the spool box and has a controlling lever H secured on the end thereof inside of the spool box. On the end of the shaft 27 is arranged a lever 28 from which extends upwardly a link 29 adjustably secured to which is a staggered arm 30 which connects by link 31 to a pivoted bell crank lever 32 extending from which is a link 33. Adjustably secured to this link 33 is a link 34 which is secured

to a pivoted lever 35, the upper end of which has a pin 36 which fits into the grooved collar 180. By these connections, by throwing the end of the controlling lever H upwardly, the mechanism will be set so that the note-sheet E will be drawn forward over the upper tracker B and the lower note-sheet E' will be drawn backwardly or rewound over the lower tracker C, as shown in Fig. 2, while by throwing the controlling lever H downward, the mechanisms will be set so that the note-sheet E' will be drawn forward for playing over the lower tracker C, and the note-sheet E will be drawn backwardly over the upper tracker B or rewound on its music roll, this position of the parts being indicated in Fig. 1.

It is also necessary, in connection with the mechanisms, to provide a switching mechanism to control the trackers so that only the tracker on which the note-sheet is being drawn forward for playing will be connected to the operating instrumentalities or pneumatics of the instruments; and it is also necessary to provide valve mechanism so that the pneumatic motor which is operating to draw its controlled note-sheet forward for playing can have its speed governed, while the pneumatic motor which is operating to draw its controlled note-sheet backwardly or rewind the same can run at full speed. It is also necessary and desirable to coördinate these instrumentalities so that they will be adjusted in unison. The mechanism for this purpose is arranged as follows:—I designates the wind chest and J the usual governing box in which there is arranged a tempo controlling valve W which is operated by link 36, lever 37, link 38, and finger lever 39. This latter lever also connects by link 40, lever 41, shaft 42, lever 43, link 44 to an indicator 45 arranged in position to coöperate with the scale 46 so that the tempo adjustment of the instrument is readily discernible to the operator. The usual motor feed pipe 47 is connected to the top of the governing box J and the tension induced in this pipe is controlled by the governor and by the adjustment of the tempo valve, and hence the speed of the motor which is operating to draw its controlled note-sheet forward is regulated by the finger lever 39.

The pipe 47 is connected to a pipe 48 which is connected to the lower side of a valve block K and to the upper side of a valve block L. Coöperating with the upper valve block K is a D- or slide valve M, and coöperating with the lower block L is a similar D- or slide valve N. These valves are held in position by springs 49. The link 38 connects to a bell crank lever 50 which connects by a link 51 to the lower slide valve N and the two slide valves are connected together by links 52 and 53 which

are adjustably secured together by a coupling 54. By this arrangement, when the controlling lever H is in its upper position, as shown in Fig. 2, the valves M and N are in their lowest position to render the upper motor G operative for drawing the note-sheet E forward for playing, while when the controlling lever H is in its lower position, the valves are in their upper position, as indicated in Fig. 1 to make the lower motor G' operative for drawing the note-sheet E' forward for playing. A pipe 55 is connected directly to the wind chest and to a block 56 extending from the lower valve block L, and the block 56 is connected by a pipe 57 to a pipe 58 extending from the side of the upper valve block K. A passage 59 extends from the block 56 inside of the lower valve block L and a passage 60 extends from the upper pipe 58 into the upper valve block K. A passage 61 is formed in the lower valve block L, and a passage 62 in the upper valve block K to connect to the pipe 48. The lower valve block L has a passage 63 and the upper valve block K has a passage 64 formed through the same. By these arrangements, when the controlling handle H is in its upper position, the tension obtained by the governing apparatus and adjustment of the tempo valve J in the pipe 47 will be connected to the passage 64 and hence the upper motor G will operate at a governed speed, depending upon the adjustment of the tempo valve, while the directly connected pipe 55 will be connected to operate the lower motor G' at the full speed, depending upon the tension in the wind chest. When the handle H is in its lower position, the connection to the motors will be reversed.

Now referring to the switching mechanism which controls the connection of the tracker to the operating instrumentalities of the instrument, 65 and 66 designate the tubes extending from the apertures in the upper tracker B and 67-68 designate tubes extending from the apertures in the lower tracker C. These tubes are connected to a switch block 69 which is illustrated more particularly in the third sheet of the drawings. Connected to this switch block are tubes 70 and 71 which extend to the pneumatics or playing instrumentalities of the instrument. 72 designates a valve carrier which has a plurality of valves 73 secured thereto. Each valve 73 has projecting pins 74-74 which fit into holes formed in the valve carrier 73 and a spring 75 is fitted on a seat formed on the valve to keep the same in position on the valve carrier 72. Each valve is preferably arranged to have four passages 76 therein so as to control the switching of four tubes. When the carrier 72 is in its lowest position, as shown in Fig. 6, the tubes 65 and 66 coming from

the upper tracker B are connected to the tubes 70-71, while when the valve carrier 72 is in its highest position, the tubes 67-68 coming from the lower tracker are connected to the lower tubes 70-71.

The valve carrier is operated by the following connections:—The link 29 is connected to an arm 77 secured on a shaft 78 journaled in the back of the spool box secured on which shaft are arms 79-79 which connect by links 80-80 to the valve carrier 72. By this arrangement, when the controlling lever H is in its raised position, the valve carrier 72 will be in its lower position and the upper tracker will be operatively connected to the operating pneumatics of the instrument and the lower tracker cut out therefrom, while when the controlling lever H is in its lower position, the valve carrier 72 will be lifted to its upper position and the lower tracker will be operatively connected to the operating pneumatics and the upper tracker cut out.

As the handle H, by the connections above described, also gives the proper connection of the motors to the wind chest, it will be seen that when the handle is raised and the upper tracker is operatively connected, the upper motor G will work at the governed adjusted speed and the lower motor at full speed for rewinding, and that when the operating handle H is lowered and the lower tracker operatively connected, the lower motor will work at the governed adjusted speed and the upper motor will work at full speed. Thus all that is necessary to give the proper adjustment between the coöperating instrumentalities is the manipulation of the controlling handle H.

It is desirable, additionally, to provide means whereby each motor can be started and stopped in operation, and the following parts are provided for this purpose:—An arm 81 is arranged inside of the spool box and is formed on the end of a shaft 82, which is journaled in the spool box and in a suitable bearing and which has an arm 83 thereon which is connected by links 84 and 85 having an adjustable coupling between them, to a valve 86 arranged between the valve block K and the upper pneumatic motor G. The arms 81 and 83 are oppositely disposed on the shaft 82. Hence, when the arm 81 is in lowest position, the valve block K is operatively connected to the motor G, while when the arm 81 is in its highest position, the valve block is cut off from connection to the motor G. Hence, the operation of the motor G, either at the governed adjusting speed obtained through the pipe 47 or at full speed, as obtained through the pipe 55, is controlled by said arm 81. A similar arm 87 is arranged on a shaft 88 secured to which is an arm 89 connected by links 90 and 91 having an adjustable cou-

pling, to a valve 92 arranged between the lower valve block L and the lower pneumatic motor G'. Hence, by the arm 87 the operation of the lower pneumatic motor G' can be started and stopped either at the governed adjusted speed for playing, or at the full speed for rewinding. Therefore, by the mechanisms described, the results previously mentioned can be obtained.

10 For illustration, a music sheet E can be put in position to coöperate with the upper tracker B and the mechanism set in position to use this note-sheet by lifting the handle H. Arms 81 and 87 should be in elevated 15 position. After the upper note-sheet E is in position, the instrument is set in operation by lowering the arm 81 whereby playing will take place from the upper note-sheet and during playing the tempo can be controlled by lever 39. As this playing operation takes place, a note-sheet E can be placed in position to coöperate with the lower tracker C. If while playing, it is desired to switch from the piece of music contained on 20 the upper note-sheet to the piece of music contained on the lower note-sheet, all that is necessary is to depress the handle H and raise the arm 81 and lower the arm 87, when the operation will be practically instantly 25 switched to the lower note-sheet and the tempo at which this note-sheet is played can be regulated through lever 39. Switching back can be done by lifting lever H, lowering lever 81 and lifting lever 87. If while 30 playing the upper note-sheet, it is desired to rewind the lower note-sheet and put a new piece in position, or for other purposes, all that is necessary is to lower the arm 87. When playing is finished with the upper 35 note-sheet, the lower note-sheet can be set in operation. Similar manipulations can be made in connection with the lower note-sheet; that is, the playing can be switched to the upper note-sheet and switched back to 40 the lower note-sheet. The upper note-sheet can be rewound while playing from the lower note-sheet and when the playing is completed with the lower note-sheet, the instrument can be switched into operation in 45 connection with a new note-sheet placed in position relatively to the upper tracker. Thus, by the mechanisms described, playing can take place at any time, either from the upper or lower note-sheet and either note- 50 sheet can be rewound while playing is going on with the other note-sheet. Thus a compact, simple apparatus for the many purposes described, is obtained which can be manipulated and controlled by a comparatively unskilled operator.

55 The details and arrangements herein shown and described may be greatly varied by a skilled mechanic without departing from the scope of my invention as expressed in the claims.

Having thus fully described my invention, what I claim and desire to secure by Letters-Patent is:—

1. In a musical instrument, the combination of two trackers, a pneumatic motor for drawing a note sheet over the first tracker, a pneumatic motor for drawing a note sheet over the second tracker, gearing whereby the motors are connected to draw their note sheets simultaneously in opposite directions over their trackers, a single manually operable controlling device and connections from said device to said gearing, whereby movement of said device will simultaneously reverse the direction of movement of both note sheets. 70

10 2. In a musical instrument, the combination of two trackers, a pneumatic motor for drawing a note sheet over the first tracker, a pneumatic motor for drawing a note sheet over the second tracker, gearing whereby the motors are connected to draw their note sheets simultaneously in opposite directions over their trackers, a single manually operable controlling device, connections from 80

85 said device to said gearing, whereby movement of said device will simultaneously reverse the direction of movement of both note sheets, and additional manually controlled devices for stopping either motor at 90

95 will when drawing the note sheet in either direction. 100

3. In a musical instrument, the combination of two trackers, a pneumatic motor for drawing a note sheet over the first tracker, a pneumatic motor for drawing a note sheet over the second tracker, gearing whereby the motors are connected to draw their note sheets simultaneously in opposite directions over their trackers, a switching mechanism 105

110 for connecting the tracker whose note sheet is moving forward so that said tracker shall control the playing mechanism, a single manually operable controlling lever, and connections from said lever to said gearing 110

115 and to said switching mechanism, whereby movement of said lever will simultaneously reverse the direction of movement of both note sheets and will also reverse the switching mechanism. 120

4. In a musical instrument, the combination of two trackers, a pneumatic motor for drawing a note sheet over the first tracker, a pneumatic motor for drawing a note sheet over the second tracker, gearing whereby the motors are connected to draw their note sheets simultaneously in opposite directions over their trackers, a switching mechanism 125

130 for connecting the tracker whose note sheet is moving forward so that said tracker shall control the playing mechanism, a single manually operable controlling lever, connections from said lever to said gearing and to said switching mechanism, whereby movement of said lever will simultaneously 130

reverse the direction of movement of both note sheets and will also reverse the switching mechanism, and additional manually controlled devices for stopping either motor at will when drawing the note sheet in either direction.

5. In a musical instrument, the combination of two trackers, a pneumatic motor for drawing a note-sheet over the first tracker, a pneumatic motor for drawing a note-sheet over the second tracker, gearing whereby each motor can be coupled to draw its note-sheet either forward or backward over its tracker, a wind chest, a tempo valve, and passages extending from the tempo valve to said motors, a passage extending from the wind chest directly to said motors, and means including valve mechanisms whereby the motor which is coupled to draw the note-sheet forward over its tracker will be connected to the wind chest so as to be controlled by the tempo valve and so that the motor which is connected to draw the note-sheet backward over its related tracker will be connected directly to the wind chest.

6. In a musical instrument, the combination of two trackers, a pneumatic motor for drawing a note-sheet over the first tracker, a pneumatic motor for drawing a note-sheet over the second tracker, gearing whereby each motor can be coupled to draw its note-sheet either forward or backward over its tracker, a wind chest, a tempo valve, and passages extending from the tempo valve to said motors, a passage extending from the wind chest directly to said motors, valve means including mechanisms whereby the motor which is coupled to draw the note-sheet forward over its tracker will be connected to the wind chest so as to be controlled by the tempo valve and so that the motor which is connected to draw the note-sheet backward over its related tracker will be connected directly to the wind chest, and connections for adjusting said valves and said gearings.

7. In a musical instrument, the combination of two trackers, a pneumatic motor for drawing a note-sheet over the first tracker, a pneumatic motor for drawing a note-sheet over the second tracker, gearing whereby each motor can be coupled to draw its note-sheet either forward or backward over its tracker, a wind chest, a tempo valve, and passages extending from the tempo valve to said motors, a passage extending from the wind chest directly to said motors, means including valve mechanisms whereby the motor which is coupled to draw the note-sheet forward over its tracker will be connected to the wind chest so as to be controlled by the tempo valve, and so that the motor which is connected to draw the note-sheet backward over its related tracker will be connected directly to the wind chest, con-

nections for adjusting said valves and setting said gearings, and a single handle for adjusting said mechanisms and said valves.

8. In a musical instrument, the combination of two trackers, a pneumatic motor for drawing a note-sheet over the first tracker, a pneumatic motor for drawing a note-sheet over the second tracker, gearing whereby each motor can be coupled to draw its note-sheet either forward or backward over its tracker, a wind chest, a tempo valve, and passages extending from the tempo valve to said motors, a passage extending from the wind chest directly to said motors, means including valve mechanisms whereby the motor which is coupled to draw the note-sheet forward over its tracker will be connected to the wind chest so as to be controlled by the tempo valve and so that the motor which is connected to draw the note-sheet backward over its related tracker will be connected directly to the wind chest, a switching mechanism for connecting the tracker over which the note-sheet is drawn forward to operate the instrument, and connections for setting said gearings, adjusting said valves, and setting said switching mechanism.

9. In a musical instrument, the combination of two trackers, a pneumatic motor for drawing a note-sheet over the first tracker, a pneumatic motor for drawing a note-sheet over the second tracker, gearing whereby each motor can be coupled to draw its note-sheet either forward or backward over its tracker, a wind chest, a tempo valve, and passages extending from the tempo valve to said motors, a passage extending from the wind chest directly to said motors, means including valve mechanisms whereby the motor which is coupled to draw the note-sheet forward over its tracker will be connected to the wind chest so as to be controlled by the tempo valve and so that the motor which is connected to draw the note-sheet backward over its related tracker will be connected directly to the wind chest, a switching mechanism for connecting the tracker over which the note-sheet is drawn forward to operate the instrument, connections for adjusting said gearings, said valve mechanisms and said switching mechanisms, and a single handle controlling said connections.

10. In a musical instrument, the combination of two trackers, a pneumatic motor for drawing a note-sheet over the first tracker, a pneumatic motor for drawing a note-sheet over the second tracker, gearing whereby each motor can be employed to draw its note-sheet either forward or backward over its related tracker, a single manually operable controlling device, connections from said device to said gearing, whereby movement of said device will simultaneously re-

verse the direction of movement of both note sheets, and additional means for separately controlling each motor, said means including a separate manually operable 5 valve connected to each motor for throwing said motor into and out of operation.

11. In a musical instrument, the combination of two trackers, a pneumatic motor for drawing a note-sheet over the first tracker, 10 a pneumatic motor for drawing a note-sheet over the second tracker, gearing whereby each motor can be coupled to draw its note-sheet either forward or backward over its tracker, a wind chest, a tempo valve, and 15 passages extending from the tempo valve to said motors, a passage extending from the wind chest directly to said motors, means including valve mechanisms whereby the motor which is coupled to draw the note-sheet 20 forward over its tracker will be connected to the wind chest so as to be controlled by the tempo valve and so that the motor which is connected to draw the note-sheet backward over its related tracker will be connected directly to the wind chest, a valve, and 25 operating connections arranged in relation to each motor so that the same can be thrown into and out of operation.

12. In a musical instrument, the combination of two trackers; a pneumatic motor for drawing a note-sheet over the first tracker, 30

a pneumatic motor for drawing a note-sheet over the second tracker, gearing whereby each motor can be coupled to draw its note-sheet either forward or backward over its 35 tracker, a wind chest, a tempo valve, and passages extending from the tempo valve to said motors, a passage extending from the wind chest directly to said motors, means including valve mechanisms whereby the motor which is coupled to draw the note-sheet 40 forward over its tracker will be connected to the wind chest so as to be controlled by the tempo valve and so that the motor which is connected to draw the note-sheet backward 45 over its related tracker will be connected directly to the wind chest, switching mechanism for connecting the tracker over which the note-sheet is drawn forward to control the instrument, connections whereby said 50 gearings, valve mechanisms and switch mechanism can be set, a valve for throwing each motor into or out of operation, and connections whereby said valves can be set.

In testimony whereof I have hereunto set 55 my hand, in the presence of two subscribing witnesses.

THOMAS DANQUARD.
